OF BROOKLYN, NEW YORK, A CORPORATION OF WEST VIRGINIA.

AUTOMOBILE TORPEDO.

1,308,181.

Specification of Letters Patent.

Patented July 1, 1919.

Application filed April 22, 1916, Serial No. 92,869. Renewed May 23, 1919. Serial No. 299,381.

To all whom it may concern:

Be it known that I, FRANK M. LEAVITT, a citizen of the United States of America, residing in Smithtown, in the county of Suffolk and State of New York, have invented certain new and useful Improvements in Automobile Torpedoes, of which the following is a specification.

This invention aims to construct an automobile torpedo having higher speed and greater precision than those heretofore made.

Torpedo development along existing lines has apparently reached its practical limit with a speed of about 35 knots at a normal range. It is highly desirable to increase the speed in order that the object aimed at may have less time for escape by moving out of the course of the torpedo or out of range. High speed is also very important in a stern chase, for which purpose torpedoes are now available only against comparatively low speed ships. A speed of 45 to 50 knots is highly desirable.

Another desideratum of great importance is the attainment of precision of control at high speed. At present, as the speed approaches the maximum irregularities or eccentricities of operation are introduced, which seriously affect, and at times incapacitate, either the depth gear or the gyroscopic steering mechanism, or both, so that the torpedo is liable to execute erratic movements.

The present invention provides a torpedo of novel cross-section. The torpedo has two air flasks, preferably cylindrical, placed either side by side or one above the other, with tangent plates bridging over the cavities between them. The result is an approximately elliptical cross-section which is continued forward in the head and aft in the after-body and tail section, so that these also have approximately elliptical cross-sections. The motor mechanism is preferably duplicated, the twin shafts being extended in the plane of the major axis of the torpedo and the respective twin propellers displaced to opposite sides of the central axis of the torpedo, so that they operate on water somewhat removed from the hull, as in the case of twin screws of ordinary ships, and hence with greater propulsive effect and with less rolling tendency.

The new construction, as compared with existing torpedoes, carries twice the quan-

60 tity of compressed air, and with twice the quantity of fuel and with the motor or turbine suitably proportioned, develops twice the propulsive energy. If the resistance to be overcome were increased in this same proportion, no material advantage would result from the increased power and size; but by reason of the new contour the wetted surface instead of being doubled, is increased only about 1.26 times that of a torpedo having a single air flask of the same size and otherwise of normal proportions. 65 In proportion to the propulsive energy the resistance is thus diminished about 37%, whereby the speed is considerably increased. 70 The new proportions also result in a marked diminution of the drag and other disturbances due to cavitation, as will be explained hereinafter.

In the following description it will be assumed that the two air flasks are placed one above the other so that the major axial plane of the torpedo is a vertical plane.

In the accompanying drawings which illustrate the preferred construction and proportions,

Figure 1 is a side elevation, mainly in vertical mid section;

Fig. 2 is a plan, partly broken away, in horizontal section;

Fig. 3 is a transverse section through the air flasks, in the plane of the line 3-3 in Fig. 1;

Fig. 4 is a transverse section in the plane of the line 4-4 in Fig. 1, and showing the motor mechanism;

Fig. 5 is a stern elevation.

Fig. 6 is a diagrammatic plan of an ordinary torpedo as heretofore constructed, and Fig. 7 is a similar diagrammatic plan illustrating the torpedo provided by the present invention.

Referring to the drawings, A is the torpedo hull as a whole, this hull being built up of sections somewhat as usual, including the head B, air flask section C, the after-body D and the tail section carrying the propellers, which, as a whole, is indicated by E. These respective sections are commonly united detachably in some suitable manner, a construction which may conveniently be followed in this improved torpedo.

The flask section C is made up of two air flasks, C¹, C², shown as placed one above

- the other and suitably connected together, as by a succession of bridge bars F, F, a suitable construction for which is shown in Fig. 3. These bridge bars may be suitably spaced 5 so as to connect the respective flasks with the requisite strength. The hull is carried across between the laterally salient portions of the respective flasks by means of plates G, G, which are preferably flat and which 10 tangent the circles forming the exteriors of the respective flasks, as clearly shown in Fig. 3. There are thus formed two approximately triangular chambers H, H between the air flasks and on opposite sides, it 15 being a function of the hull plates G, G to isolate these chambers from the exterior water and thereby reduce the wetted surface which generates skin friction when the torpedo is in motion.
- 20 Each of the air flasks is, or may be, of precisely the same construction as has heretofore been usual. From the air outlet opening *a* of each air flask there leads a tube *b*, which tubes unite and lead to a starting 25 valve *c* of any usual construction, which is connected to, and operated by, the usual starting hook *d* in any usual or suitable way. From the valve *c* the compressed air passes successively through two reducing valves *e* 30 and *f*, and from the latter, whereby it is reduced to approximately the working pressure, it is led by a tube *g* to the usual combustion chamber or heater *h*, and thence by a pipe *i* to the nozzle *j* of the usual turbine I 35 (or any other suitable motor engine) for driving the torpedo. For maintaining combustion in the heater *h* liquid fuel is fed from any suitable fuel reservoir *k* which receives air under pressure at its upper side 40 from the tube *g*, and the fuel flows therefrom through a tube *l* to the usual fuel inlet of the heater.
- In the construction shown the turbine I is 45 of the same construction as that shown in U. S. patent to F. C. B. Page, No. 1,155,485, dated October 5, 1915, to which reference may be made for a full description thereof and of the connected gearing.
- The turbine shaft *m* is extended above and 50 below the turbine wheels and carries pinions *n*, *n* and *p*, *p*. The pinions *p* mesh with gear wheels *q*, *q*; the pinions *n* mesh with idler pinions *r*, *r*, which in turn mesh with gear wheels *q'*, *q'*. The gearing ratio is such that 55 the gears *q*, *q'* of each set of gears turn in opposite directions at precisely like speeds. These gears carry bevel pinions which drive bevel gears *s*, *t* fixed respectively on the inner and outer propeller shafts in precisely 60 the manner illustrated in said patent, and which, being a well-known arrangement, requires no further description. The outer propeller shafts to which the aft bevel gears *t* are fixed are lettered J, J, and these shafts 65 carry as usual the forward propeller screws

K, K. The inner propeller shafts which are extended within the shafts J, and which consequently are not shown, carry as usual the aft propeller screws L, L. This arrangement differs from the usual one solely in 70 that the gearing group is duplicated, as also are the respective propeller shafts and screws. The shafts J, J extend parallel with each other and with the central axis of the torpedo, and are sufficiently far apart to give 75 room for the upper and lower propeller screws to turn wholly outside of the torpedo hull. The aft ends of the propeller shafts are carried in suitable out-board bearings *u*, *u*, such as are used for supporting twin 80 screw propellers on ships, these bearings being mounted on brackets M, M which are extended beyond the bearings and terminate in guiding slides N, N which are designed to move in suitable guides in the launching 85 tube. The brackets M, M act also as fins to steady the torpedo and resist rolling.

The exhaust air from the turbine passes mainly through a central exhaust conduit P and escapes through the usual sea valve Q 90 into the tail section, whence it is discharged at the tail of the torpedo through a discharge conduit P'. This discharge conduit is extended to a point aft of the propeller screws, and is of flattened cross-section 95 where it projects between the screws, as shown in Fig. 5, and serves thus the double purpose of discharging spent air and of forming a partition between the upper and lower screws, which has the function of preventing interference between the currents of water created by the respective screws.

The steering of the torpedo is performed in the same manner as heretofore by the usual depth mechanism or diving gear, and 105 the usual gyroscopic steering means. The depth mechanism comprises the usual pendulum R and the usual hydrostat R' and depth engine S, the plunger of the latter being connected as usual through the tiller rod 110 *w* to the tiller of the depth rudder T. The vertical rudders U for steering in the horizontal plane are operated in the usual way from a gyroscopic steering mechanism. These mechanisms are essentially of the 115 usual construction, such as shown in detail in U. S. Patents Nos. 1,080,116, dated December 2, 1913, 1,148,155, dated July 27, 1915, and 1,153,678, dated September 14, 1915. The hydrostat casing V may be advantageously extended athwartships as shown.

In the construction shown the bridge bars F, F are attached by bolts or other suitable means to the respective air flasks C¹, C², and for this purpose the flasks are formed with 125 internal bosses *x*, *x* to receive the bolts or other fastenings. The bars F, F are ribbed on their inner sides for strength, and are flattened on their outer faces to afford a seat for the hull plates G, G which are fastened 130

to them and to the flasks in any suitable way, as by riveting or welding. The chambers H, H may be filled with any suitable liquid if ballast is required, or if not, may be filled 5 with air or other gas.

With an ordinary torpedo having a single cylindrical air flask, this flask forms throughout its length the hull or shell of the 10 torpedo and determines the outlines of the head and after-body, both of which are of circular cross-section at all points. With the improved torpedo having two air flasks, assuming these to be of the same size as heretofore, the cross-section is increased to 15 double that of a single flask, plus the area of the two chambers H, H; but the perimeter which determines the wetted surface, and hence the skin friction, is increased in much smaller proportion. The perimeter equals 20 the circumference of one flask plus twice the distance between centers. Thus, while the stored energy is doubled the perimeter is only about 1.66 times the circumference of a single flask, and the total wetted surface 25 and consequent skin friction are increased in a somewhat smaller proportion, viz., by 1.26. Thus, by proportioning the turbine to receive twice the volume of air at the same working pressure as heretofore, it delivers 30 to each group of gearing and to each pair of propeller screws, the same propulsive energy as has heretofore been imparted in the ordinary torpedoes to one pair of propeller screws. It results that the propulsive 35 energy of the torpedo is doubled, while its skin friction is increased only about 1.26 times. In addition, the lateral after-body lines are much finer than in the case of a torpedo with a single flask. Furthermore, 40 the propeller screws act to greater advantage because they are removed from the hull of the torpedo at the tail section and consequently turn in comparatively undisturbed water, or, in other words, act upon solid 45 water so-called. By reason of these several differences the new torpedo is capable of a marked increase of speed as compared with torpedoes heretofore made, and under like conditions of air pressure, fuel feed and gear 50 ratios.

When a submerged body is moving through the water it parts the water at its advancing or bow end and the water flows in behind it at its following or stern end. 55 The latter operation is facilitated by giving the stern portion of the body a very gradual taper, so that this portion or after-body falls in no faster than the inertia of the water will enable it to follow in stream 60 lines. If the body moves through the water more rapidly than the water can flow in behind it, a cavity is left in the wake of the body. This phenomenon is technically known as cavitation. In the case of a tor- 65 pedo cavitation becomes important when

traveling at high speed. With a torpedo the cavity, instead of being a vacuum, is likely to contain air, either rarefied or possibly even under pressure, the presence of air being due to leakage of the exhaust air from 70 the motor through joints in the hull or around the propeller shafts; and because of this introduction of air into the cavity the latter becomes larger than if it were a vacuum, so that cavitation troubles in a 75 torpedo are liable to become serious. Fig. 6 illustrates a serious case of torpedo cavitation, the dotted line x—x indicating approximately the boundary of the cavity. Cavitation involves that the propeller 80 screws instead of turning effectively in solid water, turn partially in the cavity, and to that extent are ineffective; thus cavitation tends to remove the solid or undisturbed water from the center so that only the outer 85 portions of the screw blades act upon solid water, resulting in ineffective action or slip. This slip is not serious with existing torpedoes in running on a straight course at a speed not exceeding 35 knots; but above that 90 speed the cavitation produces progressively increasing slip, and even below that speed in traversing the curved course for an angle fire cavitation introduces difficulty because it unbalances the propellers, so that a 95 greater depth of blade is effective on one side than on the other. This is because in traversing a curved course the cavitation follows this curve so that the propeller 100 blades on the outer sides of the curve are working in solid water while those on the inner side are working in air. As the cavity, whether the course be straight or curved, tapers aft, it follows that the forward propeller screw turns in a larger cavity than the 105 aft one, so that the latter becomes the more effective and has a tendency to cause the torpedo to roll. This tendency has been heretofore apparent only during angle fire. At 110 higher speed the same difficulty would be 115 encountered when on a straight course. This rolling tendency is highly disadvantageous because it tends to incapacitate the steering mechanisms; if the rolling reached 90° the vertical rudders would become horizontal 120 and the horizontal rudders would become vertical, so that the steering control mechanisms would become wholly ineffective and highly erratic movements would result; and any degree of rolling tends proportionately 125 to approach this condition. Precision in a torpedo is dependent upon maintaining the most effective steering control, and this involves avoidance of any material rolling. Heretofore to avoid rolling on a curved 130 course it has been found necessary to alter the pitch of one screw so as to partially balance their efficiency on a curved course; but this has the disadvantage of oppositely affecting their relative efficiency on a

straight course, or at lower speed where less cavitation exists. Cavitation also limits speed, because the higher the speed the longer the cavity, and hence the shorter the effective tip portions of the blades, which alone turn in solid water; hence, as speed is increased screw efficiency is diminished until a point is reached beyond which no acceleration is possible. Approaching this limit the 10 irregular action due to rolling becomes so marked that the torpedo executes prohibitively erratic movements.

The improved torpedo provided by the present invention largely avoids the disadvantages due to cavitation by reason of the relatively narrower or flatter contour of the after-body, which thus falls in more gradually in proportion than with the torpedoes heretofore used; and because also of the propeller screw axes being located as remotely as possible from the torpedo axis, so that these screws turn outside the hull where they act mainly outside the region of cavitation. Rolling troubles are diminished also because 25 of the non-coincidence of the screw axes with the torpedo axis, so that the propeller screws are less effective to roll the torpedo, even if unbalanced. The propellers are removed so far from the center of the torpedo that it 30 would probably be practical to use a single upper propeller and a single lower propeller turning in opposite directions.

An important advantage of the invention is that the shape of the war head is altered, 35 so that for the same cubical contents the mass of explosive is brought closer to the target, whereby the explosion is given a greater destructive effect. This is due to the doubling of the width (height) of the war 40 head adjacent the air flasks, whereby the forward projection of the war head may be diminished. Because of this the air flasks (for a torpedo of given length) are displaced forward to the extent shown by comparing Fig. 45 6, which illustrates the ordinary single flask torpedo, and Fig. 7, which shows in plan the new double flask torpedo. This forward displacement of the heavy air flasks carries the center of gravity farther forward and enables the displacement of the after-body to 50 be diminished by reducing the cross-section of the hull at all points between a transverse plane slightly aft of the flasks and a transverse plane slightly forward of the screws. 55 It thus results that the after-body has much finer lines than have heretofore been possible. It is in large part to this change that the diminution in cavitation is due.

With this new torpedo, while with the air 60 flasks of a given size the propulsive power is doubled, the total displacement is less than double because although the motor weight due to the gearing, shafts and propellers is doubled the motor itself, and the valve group 65 and control mechanisms are not doubled, be-

ing of practically the same weight as in a single flask torpedo. This difference contributes to finer after-body lines and permits higher speed, while diminishing the cavitation.

As above indicated, one of the most serious disadvantages of cavitation in a torpedo is that a large proportion of the area of the propeller screws is rendered ineffective by acting upon air or foam instead of upon so-called solid water. To attain high speed it is requisite that a sufficient area of the propellers shall act against substantially unyielding water to enable the engine to exert through the propellers the backward thrust against the water which corresponds to such speed. The present invention attains higher speed principally by making the propeller more effective, and this is due in part to the diminution of cavitation by reason of the changes above described, and in part to the location of the propellers on axes as remote as practicable from the central longitudinal axis of the torpedo, so that as much of the area of the propellers as possible is brought outside the region of cavitation.

It must not be inferred from the detailed description of the accompanying drawings hereinbefore given that the invention is necessarily limited to the constructional features and details set forth, as it is susceptible of a considerable range of modification. As above stated, the construction may be modified to locate the two air flasks side by side instead of one above the other, which involves merely a re-arrangement of the control mechanism; also, from each pair of propeller screws one screw may be omitted, together with its connected shaft and gearing, so as to reduce the screws to one above and one beneath, turning in contrary directions. Other possible modifications will be apparent to those skilled in the art.

I claim as my invention:—

1. An automobile torpedo having two elongated cylindrical parallel longitudinal air flasks forming part of the transverse contour of the torpedo hull, and comprising propulsive mechanism driven by air supplied from both flasks.

2. An automobile torpedo having two parallel air flasks, and means for bridging the cavities between them whereby to afford a continuous hull surface of substantially minimum perimetral dimensions.

3. An automobile torpedo having two parallel air flasks, and substantially flat hull plates bridging the cavities between them.

4. An automobile torpedo having two parallel air flasks, and means for bridging the cavities between them, comprising transverse bridge bars attached to the respective flasks and hull plates covering said bridge bars.

5. An automobile torpedo having two elongated cylindrical air flasks arranged

parallel and longitudinally of the torpedo and forming part of the main hull, such hull being flattened and conforming mainly to the flask in transverse contour, and the head 5 and tail of the hull extended beyond the flask and flattened in conformity to the intermediate hull portion.

6. An automobile torpedo having a flattened hull, comprising two parallel air 10 flasks forming part of such hull, and having propeller screws turning on axes on opposite sides of the central torpedo axis, said axes coinciding with the axes of the flasks, and intervening motor mechanism for driving 15 such screws.

7. An automobile torpedo having a flattened hull, comprising two parallel cylindrical air flasks forming part of such hull, a single motor receiving air from both flasks, 20 and propeller screws turning on axes coinciding with the axes of said flasks, and driven respectively from said motor.

8. An automobile torpedo having a flat-

tened hull, comprising two parallel cylindrical air flasks, forming part of such hull, 25 a single motor receiving air from both flasks, and two pairs of propeller screws, the respective pairs turning on axes coinciding with the axes of the respective flasks, with interposed gearing whereby the screws of 30 each pair turn in opposite directions.

9. An automobile torpedo having a flattened hull and comprising two parallel cylindrical air flasks, forming part of the hull of the torpedo, screw propellers on axes 35 coinciding with the axes of the flasks, a motor for driving said propellers, and air connections from both flasks to such motor.

In witness whereof, I have hereunto signed my name in the presence of two subscribing 40 witnesses.
